United States Patent Office

Des. 225,801
Patented Jan. 9, 1973

225,801

CHAIR

Frank R. Torrey, 9305 Dallas Ave.,
Silver Spring, Md. 20901

Filed Feb. 19, 1971, Ser. No. 117,178

Term of patent 14 years

Int. Cl. D6—02

U.S. Cl. D6—75

FIG. 1

FIG. 4

FIG. 2

FIG. 5

FIG. 6

FIG. 3

FIG. 1 is a perspective view of a chair showing my new design;

FIG. 2 is a rear elevational view thereof;

FIG. 3 is a left side elevational view, the right side being a mirror image thereof;

FIG. 4 is a modified form of the chair, shown in perspective;

FIG. 5 is a rear elevational view of the chair of FIG. 4;

FIG. 6 is a left side elevational view of the chair shown in FIG. 4, the right side being a mirror image thereof.

I claim:

The ornamental design for a chair, as shown and described.
